EXPANSIBLE CONNECTOR

Willy Mauch, Bridgeport, Conn., assignor to
Bruner-Ritter, Inc., New York, N. Y., a corpora-
tion of New York

Application February 16, 1945, Serial No. 578,167

9 Claims. (Cl. 24-71)

1

This invention relates to bracelets or connectors and relates more particularly to an extensible attachment or clasp for wrist watch straps or the like.

Connectors of the type to which the present invention relates are well known and provide a means whereby a bracelet or strap may be enlarged to slip over the hand and contracted to hold a watch or ornament in place on the wrist.

A popular type of connector consists of a plurality of foldable members which are hinged together and fold or unfold to contract or expand the bracelet. Means are also provided whereby after the members are folded an additional contraction is possible by an independent movement of one of the members or by an auxiliary member.

Most foldable connectors when folded are held in fixed closed relation by friction contact members usually in the form of a lug on one member engaging a flange on another member. It has been found in practice that after relatively limited use the wear on the lug or flange results in failure to hold the members with the security desired for practical purposes.

Various forms of means have been proposed to lock the members in fixed relation when folded but devices of this kind have been attended by certain disadvantages in that they lacked the feature of the additional take-up or if a take-up was provided it required the operation of releasing means difficult for the wearer to manipulate.

It is an object of the present invention to provide a connector of simple construction and which may be readily contracted and automatically locked and unlocked.

Another object of the invention is to provide a connector or clasp of the foldable type which by the simple operation of folding a plurality of members to contract a bracelet is in condition to be further contracted by a movement of a slide member which latter serves to positively lock the members in fixed relation.

Another object of the invention is to provide a foldable clasp with a slideable take-up member so constructed as to lock or release the foldable members by a slight endwise movement of the take-up member.

Another object of the invention is to provide a slideable take-up member so constructed and arranged as to either lock or release the slideable members at any one of a plurality of positions along the path of movement of said slideable member.

Another object of the invention is to provide a connector with a plurality of foldable members one of which carries a toothed member to be engaged by a pawl carried by another foldable member with resilient means for holding the pawl and toothed member engaged.

2

Other objects and advantages of the invention will be evident from the following description together with the accompanying drawing, in which:

Fig. 1 is a perspective view of a connector constructed in accordance with the present invention.

Fig. 2 is a view taken on line II-II in Fig. 1 but showing the foldable members in closed or folded relation.

Fig. 3 is a fragmentary perspective view of one end of a slideable take-up member.

Fig. 4 is a fragmentary portion of Fig. 2 but with pawl of the slideable member in position to travel over one of the teeth of a ratchet.

Fig. 5 is a view similar to Fig. 4 but shows the pawl engaged by a tooth of the ratchet.

Fig. 6 is a view taken on line VI-VII in Fig. 5.

Fig. 7 is a view illustrating the operation of adjusting the take-up member after the foldable members are folded to contract the connector.

Fig. 8 is a view similar to Fig. 7 but shows the position of the fingers when the foldable members are ready to unfold.

Fig. 9 is a side view of the connector with the foldable members in folded relation and the slideable member ready to be adjusted.

Fig. 10 is a view of the underside of the connector with the foldable members unfolded and the slideable member extended.

Fig. 11 is a fragmentary cross sectional view of the connector showing a different form of ratchet.

Fig. 12 is a fragmentary cross sectional view of the folded members but shows the ratchet teeth extending in a direction opposite to that shown in the other views, and

Fig. 13 is a view taken on line XII-XII in Fig. 12.

In accordance with the present invention, one practical embodiment thereof may comprise a plurality of foldable members 10, 11 and 12. The member 10 is connected to one end of member 11 by a hinge 13 and the other end of member 11 is connected to one end of member 12 by a hinge 14.

The member 10 which may be termed the top or cover member is of trough shape having guide channels 15 and 16 along its sides to receive a slide member or take-up element 17 therebetween. In the construction shown the slide member 17 is formed with slide rods or rails 18 and 19 movable in channels or guiders 15 and 16 respectively, integral with the cover member 10. Adjacent to the inner ends of the slide rods 18 and 19 is a cross piece or strut 21 and near the ends of the rods are provided pins or pawls 22 and 23. The opposite end of the slide member 17 has a cross bar 24 which may be connected to any selected type of bracelet 25 by a suitable coupling 26. The slide member 17 serves as a take-

up or adjustment element and is normally urged to its outer or extended position by coiled springs 28 disposed in the channels 15 and 16. The springs engage closed ends 29 of the channels and the ends 30 and 31 of the bars 18 and 19 respectively.

The springs 28 are so constructed and arranged that when expanded the slide-member 17 is moved to its outer or extended position ready for adjustment to cause the pawls 22 and 23 to engage teeth 32 and 33 or a ratchet 33' carried by the foldable-member 12. This member 12 may, as shown, be formed with flanges 34 and 35 to provide the teeth 32 and 33 and inclined surfaces or cam members 36 and 37 for purposes to be described.

When the foldable members 10, 11 and 12 are in closed or folded relation the member 11 seats between the flanges 34 and 35 of the member 12. The cover-member 10 seats over the member 11 and the flanges 34 and 35 are disposed between the channels 15 and 16 of the member 10. This brings the teeth 32 and 33 in position to be engaged by the pawls 22 and 23, when the slide-member 17 is moved inwardly for adjustment purposes.

When the slide-member 17 is in its extreme outer position and the foldable members are in closed relation the pawls 22 and 23 are disposed in depressions or notches 38 and 39. The connector may then be operated as shown in Fig. 7 to adjust the slide or take-up member 17 to contract the connector and tighten the bracelet about the wrist.

When making this adjustment of the connector the thumb is applied to the extended end of the slide-member while one finger holds the top member 10 from lifting as the slide-member is moved, to cause the pawls to travel over the upper surfaces 41 of the teeth of the ratchet as shown in Fig. 4. As the slide-member is moved inwardly to an adjusted position the pawls drop into elongated slots 40 between the teeth. Since the springs 28 exert a force to move the slide-member in a reverse direction a release of the slide-member permits the springs to move the pawls to the ends of the slots 40 on the teeth. Thus when the pawls are disposed beneath the extended teeth the teeth or extensions thereof serve as lock members preventing accidental lifting or unfolding of the foldable members, as shown in Figs. 5 and 6.

When it is desired to open the connector the thumb is pressed against the slide-member as shown in Fig. 8 and this member is moved against the opposition of the springs until the pawls ride up the inclined surfaces or cams 36 and 37. This movement of the pawls causes the cover 10 to lift and the foldable members to separate and readily open to expand the bracelet for removal over the hand.

As above described the slide-member may be moved from its extreme outer position to an adjusted position. It will be evident, however, that even if the slide-member is in an intermediate position the foldable members may be closed since the pawls will enter a slot and immediately the springs will cause the pawls to be held beneath the extended teeth to lock the foldable members in fixed relation. Furthermore it is not necessary to move the slide-member to its extreme inward position to release the foldable members. If the slide-member is moved sufficiently in opposition to the springs to bring the pawls from beneath the extended teeth and

the cover member 10 is lifted the foldable members will be released. The opening of the clasp when the slide member is not in its extreme inward position may or may not be practiced depending on the desire of the user since whereas the extreme inward movement of the slide member automatically separates the foldable members, it is necessary for the user to exercise some degree of manipulation to release the foldable members when the pawl and ratchet are engaged. The complete inward movement is a simple operation, and serves to lift the cover member 10, greatly simplifying the operation of opening the clasp, which is an advantage in devices of this type.

It is also possible with the present construction to close the connector even if the slide-member is in such position that the pawls are over the ratchet since pressure on the cover member will cause the pawls to enter a slot between teeth and the springs will instantly cause the pawls to move beneath the extensions of the teeth and lock the foldable members in closed relation.

The above described invention may be modified in specific structure as for example instead of two rows of teeth only one row may be necessary, particularly in the smaller size device as provided for a lady's wrist watch.

Furthermore, instead of the rigid pin type pawls a spring or resilient pawl 42 may be employed as shown in Fig. 11. This pawl may be attached to or may be stamped from the cross piece 21 of the slide-member 17. In this construction ratchet teeth 43 are provided with slots inclined with respect to the path of movement of the pawl 42 during its travel with the slide-member 17. The slots are so formed as to provide teeth 43 with inclined surfaces to engage the pawl which will be held against an inclined surface of a tooth by the expansive action of the springs 28. Figs. 12 and 13 show a construction in which the cover is opposite to the rear side of the ratchet so that the pawls travel between the bottom member and the ratchet teeth.

In accordance with the foregoing description the pawls 22 and 23 engage the ratchet upon movement between the teeth and the top member and as shown an extreme inward movement of the slide-member 17 cause the pawls to ride up cams 36 and 37 to separate the foldable members. In Figs. 12 and 13 a slide-member 44 is provided with pins or pawls 45 and 46 to engage with teeth 47 and 48 of a ratchet 49. In this construction the top-member or cover 50 is generally the same as the cover member 10 connected to the bottom member by member 59'. The bottom member 51 is of trough shape having flanges 52 and 53 folded over to provide material for the formation of the teeth 47 and 48. These teeth as shown are inclined and project toward the bottom member 51. As the slide-member 44 is moved inwardly the pawls ride over the teeth in opposition to a force exerted by springs 55 disposed in channels 56 and 57. As the pawls travel the release of the slide-member permits the springs to cause the pawls to enter a slot at the adjusted position of the slide-member. When the pawls have moved into the slots the springs hold the pawls firmly in place while the inclined formation of the teeth serves to prevent a lifting of the top-member whereby the foldable members are locked in fixed relation. When it is desired to open the connector by unfolding the foldable members, the slide-member is moved inwardly in opposition to the action of the springs until the pawls pass the last of the teeth of the ratchet.

When the pawls clear the teeth a release of the slide-member permits the springs, which have been compressed, to expand and the pawls ride over cam surface 58 and since the pawls are integral with the slide-member and the slide-member is carried by the top-member, it will be evident that the top and bottom foldable members will be forced apart, facilitating the operation of unfolding the foldable members to expand the connector. The slide-member is obviously free to move to its outer or extended position under the action of the springs 55, hence the complete opening or expansion of the connector is substantially automatic.

It will be evident from the foregoing that the present invention provides an improved connector or clasp of the foldable type which when closed or folded may be adjusted and held in a plurality of adjusted positions to hold the foldable members in locked relation, and further provides means operable upon a movement of the slideable-member for automatically causing a partial separation of the foldable members which greatly facilitates the operation of expanding the connector by the user for removal from the wrist.

Although a preferred embodiment of the invention is shown and described herein, it is to be understood that modifications may be made in the construction without departing from the spirit and scope of the invention as set forth in the appended claims.

I claim:

1. A connector having a plurality of foldable members comprising a slide-member movable endwise in one direction relative to one of said foldable members to extend said connector, means on one of said foldable members engaging said slide-member to hold said foldable members in fixed folded relation when folded, and means for causing a separation of said foldable members upon a movement of said slide-member in an opposite direction.

2. An extensible connector for a bracelet comprising a plurality of members hinged together to fold or unfold to contract or expand the bracelet, a slide-member carried by one of said members and movable endwise to increase or decrease the length of the connector, means for holding the members in folded fixed relation, and means for causing a release and separation of said members upon a selected movement of said slide-member.

3. An extensible connector for a bracelet comprising a plurality of members hinged together to fold or unfold to contract or expand the bracelet, a slide-member carried by one of said members and movable endwise to increase or decrease the length of the connector, resilient means for normally moving the slide-member to an extended position, means on another of said members for engaging said slide-member to hold the members in fixed folded relation, and means for causing a release of said members upon a selected movement of said slide-member in a direction opposing the force exerted by said resilient means.

4. A connector having a plurality of foldable members comprising a slide-member movable in guides on one of said foldable members, a pawl on said slide-member, a ratchet on another of said foldable members said pawl and ratchet cooperating when engaged to hold said foldable members in fixed folded relation when folded and a resilient member for holding said pawl engaged with said ratchet.

5. A connector having a plurality of foldable members comprising a slide-member movable in guides on one of said foldable members, a pawl on said slide-member, a ratchet on another of said foldable members, said pawl and ratchet cooperating when engaged to hold said foldable members in fixed relation when said foldable members are in folded relation and means for causing a separation of said foldable members upon a movement of said slide-member.

6. An extensible connector comprising a plurality of members hinged together to fold or unfold, a slide-member movable in one of said members, a resilient member for normally urging said slide-member to an extended position with respect to said member, means on another of said members for engaging said slide-member to hold said members in fixed folded relation when folded, and means on said slide-member and another of said members for causing a separation of said members when said slide-member is moved toward said resilient member.

7. A connector having a plurality of foldable members comprising a slide-member carried by one of said foldable members, means on another of said slideable members for engaging said slide-member to lock the foldable members in fixed relation when said members are folded and a resilient member for holding said means engaged with said slide-member.

8. A connector having a plurality of foldable members comprising a slide-member movable endwise in guides on one of said foldable members, a pawl on said slide-member, a plurality of teeth on another of said foldable members for engaging said pawl to hold said members in fixed relation when folded, a spring for moving said slide-member in a direction to be engaged by one of said teeth to lock said foldable members in fixed folded relation when said slide-member is in one of a plurality of adjusted positions, and means integral with said teeth for causing a separation of said foldable members when said slide-member is moved in opposition to the force exerted by said spring.

9. A connector having a plurality of foldable members, including a top-member and a bottom-member, a slide-member movable endwise in said top-member, a pawl on said slide-member, resilient means for normally moving said slide-member in one direction relative to said top-member when said members are in unfolded relation, a plurality of teeth on said bottom-member, said teeth being formed to provide slots to receive said pawl, said pawl being engageable with said teeth to prevent said foldable members from unfolding and to separate said foldable members when said slide-member is moved in an opposite direction.
